UNITED STATES PATENT OFFICE.

ALBERT D. GROVER, OF LONG ISLAND CITY, NEW YORK.

EXTENSION TAILPIECE.

Application filed February 4, 1925. Serial No. 6,746.

My invention relates to stringed musical instruments, and has particular reference to an improved extension tail-piece.

So-called "extension" tail-pieces are well-known, extending out over the head of the instrument toward the bridge. The strings generally overlie the tail-piece and are fastened in various ways to string-holding means at the base of the instrument. The object of my invention is to provide a tail-piece of this character having string-guides of such a construction that the tail-piece may be used upon instruments using any of the usual numbers of strings. A further object is to provide a cover and means for keeping it closed whereby the tail-piece and the strings will be completely covered so that possible interference with a player's sleeve will be avoided.

With these and other objects in view, the invention lies in the construction and combination of parts more fully described hereinafter, set forth in the appended claims and illustrated in the accompanying drawings, in which

Fig. 1 is a plan view of the base of an instrument, showing my improved tail-piece, with parts broken away for the sake of clarity; Fig. 2 is an elevational cross section 30 along the line 2—2 of Fig. 1; Fig. 3 is a rear elevational view of the tail-piece, showing string-holding means; Fig. 4 is a side elevational view of the tail-piece and cover in closed position; Fig. 5 is an enlarged detail end view of the forward end of the tail-piece; and Fig. 6 is a cross sectional view 35 along the line 6—6 of Fig. 1, omitting the strings.

Referring to the drawings, and particularly to Figs. 1 and 2, 10 denotes the instrument head stretched over a ring 11, and wound about a flesh hoop 12 in the well-known manner, the latter being held in place by a straining ring 13 which is in turn held 45 down by any suitable means, such as by hooks (not shown). The tail-piece is shown at 14 and comprises the well-known rim portion 15 and the head portion 16 at right angles to the rim portion and extending out 50 over the head 10. The rear or rim portion 15 may be made fast to the instrument rim by any suitable well-known means as indicated at 17.

The invention consists primarily in the 55 novel construction of the forward end of the tail-piece whereby spaced string guides are

provided. The forward or free end of the tail-piece is bent inwardly toward the instrument head, as at 18, (but does not rest thereupon), and terminates in upstanding 60 projections 19, preferably at right angles to the head portion of the tail-piece. The projections are shaped and spaced as shown in Fig. 5 and comprise a number of T-shaped projections 20 and two inverted L-shaped 65 projections 21, each of the latter being of a shape substantially identical with a half of any of the projections 20. The cross pieces of these projections comprise lateral hooks which serve as guides 22 for strings passing 70 thereunder. The projections are spaced so that these guides are equally spaced, and so that the spaces 23 between adjacent projections are also equally spaced. The spaces 23 serve as threading slots. 75

It is desirable, and I prefer, to make the guides 22 of a height approximately in a plane with the upper surface of the tail-piece, so that strings 24 (Fig. 2) may pass thereunder and continue on in a straight line 80 along the upper surface of the tail-piece. It is with this object in view, whereby sudden and unsmooth curvature of the strings is prevented, that the forward end of the tail-piece is bent inwardly to form the inclined portion 18.

I prefer to form three projections of the type of 20, whereby eight string guides in all are provided. Any of the usual number of strings used in instruments of this character, viz., 4, 5, 6, or 8, may be threaded through the guides 22. 85

On the rim portion of the tail-piece I attach string-holding means 25, preferably comprising a number of hooks 26 adapted to receive the looped ends of strings. I prefer to provide these hooks as integral with a plate 27 having knocked out tabs 28 which may be inserted through an opening in the rim portion of the tail-piece and clenched 95 back. It will thus be evident that in the assembly of the instrument it is possible to attach a plate 27 having any desired number of string-receiving hooks of any desired shape and configuration depending upon the 100 quality and kind of strings to be used. 105

The rim portion of the tail-piece is provided with ears 29 serving as pivot points for a cover having a rim portion 30 and a head portion 31 conforming substantially to the tail-piece. Its rim portion 30 has lateral flanges hinged or pivoted to the ears 29 110

as at 32, and the head portion 31 has depending flanges 33 which are spaced to frictionally engage upstanding flanges 34 of the tail-piece. The cover is made of a size to overlie the entire tail-piece, and it rests at its forward end on the tops of the projections 19, and extends beyond them to provide an overhanging portion which facilitates lifting of the cover by exertion of pressure underneath it. The space between the tail-piece and the cover constitutes a chamber 35, as shown in Fig. 6, in which the strings lie protected from contact with a player's sleeve.

I also prefer to provide flaps 36 integral with the tail-piece to rest upon the tensioning ring and keep the tail-piece firmly in position, at the same time preventing contact of the forward end of the tail piece with the instrument head 10.

The compactness, neatness, ease of threading, and general utility and appearance of the device will be apparent to anyone skilled in the art, and I do not mean to limit my self to the particular construction shown, since it is conceivable that various modifications may be made, without departing from the spirit of the invention.

What I claim is:—

- 30 1. An extension tail piece for stringed musical instruments comprising a head plate extending over the head of the instrument and having a V-shaped lip, the latter being provided with spaced slots to receive and 35 guide the strings beyond the head plate, the other end of the plate being bent at an angle to provide a rim plate the upright side portions of which are bent outwardly to form ears, and a cover plate hinged at one end in 40 said ears and having its opposite end supported on and projecting beyond the upturned edge of the lip.
2. An extension tail piece for stringed musical instruments comprising a head plate 45 extending over the head portion of the instrument and having a plurality of integral T-shaped projections cut in one end, the ends of the cross pieces of the projections being

bent at an angle to form hooks to receive and 50 guide the strings in the spaces therebetween and the portion of the head plate adjacent the projections being offset downwardly to be disposed just short of the head, a cover plate 55 hinged to the tail piece and having its free end supported on and projecting beyond the upper edge of the projections, the cover plate being further bent downwardly along its longitudinal sides to embrace the sides of the head plate.

3. An extension tail piece for stringed 60 musical instruments, comprising a head plate having integral T-shaped string guides at one end, the cross pieces of the guides being bent at an angle to form hooks, the head plate being further bent at an angle at the 65 opposite end to form a rim plate, and at the sides to form upright longitudinal side flanges, and a cover plate hinged to the rim plate and having its free end supported on and projecting beyond the said string guides 70 and its longitudinal sides bent downwardly to embrace the flanges of the head plate.

4. An extension tail piece, as claimed in claim 3, in which a section of the head plate side flanges adjacent the rim plate is bent 75 at an angle to engage and be supported by the straining ring of the instrument.

5. An extension tail piece for stringed musical instruments, comprising a head plate 80 extending over the head of the instrument and having three T-shaped projections bent at an angle and two outside inverted L-shaped projections bent at the same angle, all projections having the ends of their cross pieces bent at an angle to form hoops disposed to receive and guide the strings in the spaces therebetween.

6. An extension tail piece, as claimed in claim 1, including a string holding attachment carried by the rim plate to hold the 90 ends of the strings, substantially as described.

In testimony whereof I have affixed my signature.

ALBERT D. GROVER.
